B. P. JOYCE

GAS ENGINE OF THE TURBINE TYPE

Filed June 6, 1922

Inventor
Bryan P. Joyce
By W. N. Roach.

Attorney

UNITED STATES PATENT OFFICE.

BRYAN P. JOYCE, OF WASHINGTON, DISTRICT OF COLUMBIA.

GAS ENGINE OF THE TURBINE TYPE.

Application filed June 6, 1922. Serial No. 566,383.

To all whom it may concern:

Be it known that I, BRYAN P. JOYCE, a citizen of the United States, residing at Washington, District of Columbia, have invented new and useful Improvements in Gas Engines of the Turbine Type, of which the following is a specification.

The subject of this invention is a gas engine of the turbine type.

10 The main objects of the invention are, the provision of a simple and efficient turbine engine; and the provision of means for properly compressing the charge before explosion thereof in such a way that the force 15 of the explosion will act only on the rotor and will not affect the element used for compressing the charge.

With these and other objects in view, which will hereinafter more fully appear, 20 my invention consists in the novel arrangement and combination of parts and in the details of construction hereinafter described and claimed, it being understood that changes in the precise embodiment of the 25 invention herein disclosed may be made within the scope of what is claimed without departing from the spirit of the invention.

A practical embodiment of the invention is shown in the accompanying drawing by 30 way of illustration, wherein:

Figure 1 is a longitudinal section of an engine constructed in accordance with my invention, parts in elevation;

Figure 2 is a section on the line 2—2 of 35 Figure 1;

Figure 3 is a section on the line 3—3 of Figure 1.

Referring to the drawing by numerals of reference:

40 I provide a casing, preferably of tubular formation, having an attenuated portion 10 and a preferably integral enlarged portion 11.

Within the casing I mount a rotor having 45 a shaft-like portion 12 formed with a spiral groove 13 cut therein and extending throughout practically the entire length thereof. While I have shown and described this shaft-like portion as having a

50 spiral groove therein it is understood that runners having grooves or vanes of suitable form may be substituted for the spiral groove without departing from the spirit of this invention. Connected to the portion 12 and, conveniently integral therewith is an enlarged portion of the rotor housed

within the portion 11 of the casing and consisting of a portion 14 which fits within the casing with a close turning fit, and a cylindrical portion 15 in which is cut a cam 60 groove 16.

Encircling the cylindrical portion 15, and having a close sliding fit thereon and within the portion 11 of the casing, is a piston 17 which may be packed with rings 18. A 65 pin 19 is mounted in the piston and extends into the cam groove 16 to cause reciprocation of the piston through rotation of the rotor. Means are provided to prevent rotation of the piston; such means, as herein 70 shown, may conveniently consist of a key 20 seated in a groove in the casing and engaging in a groove extending longitudinally of the piston.

Fuel may be fed to the engine through an 75 intake pipe 21, the fuel entering to destroy the partial vacuum caused by movement rearwardly of the piston through a port 22 formed in the portion 14 of the rotor. The charge thus supplied to the engine will be 80 compressed on forward movement of the piston and will be forced through the same port 22 (keeping in mind that the parts as shown in the drawing are in the firing position and that the rotor is rotating in a 85 clockwise direction as viewed in Figures 2 and 3) and a bypass 24 into an explosion chamber 23 formed in the forward end of the portion 11 of the casing. The explosion chamber 23 is cut-off from communication 90 with the groove 13 by means of a sleeve 2 which surrounds the rotor at that portion which passes through and which is adjacent to the chamber except during the time that explosion is taking place within the 95 chamber at which time the rear end of the groove 13 registers with a slot 26 provided in the sleeve. The sleeve may be held against rotation by means of a key 25 located in alining apertures formed in the 100 casing and sleeve.

An exhaust chamber is provided at the forward end of the portion 10 of the casing with which the exhaust ports 27 are in communication.

105 A suitable gear, such as the bevel gear 28 may be mounted on the extending end of the rotor portion 11 and may be locked in place thereon by a nut 29. This gear and the portion 14 of the rotor, both abutting against the casing, will hold the rotor against rectilinear movement with respect to the casing.

Any preferred form of generator 30 and timer or distributor 31 may be connected to the rotor to supply current through a wire 32 to a spark plug 33 so that the charge in the explosion chamber may be properly ignited.

From the foregoing description it is evident that when explosion takes place all communication between the explosion chamber and the chamber in which the piston reciprocates is cut off, and that the sole purpose of the piston is to draw in the charge and force it into the explosion chamber.

I claim:

1. A gas turbine, including a casing provided with an inlet and an exhaust port, and with an explosion chamber, a rotor within the casing, said rotor provided with a spiral groove and a cam groove, and with a port adapted to alternately register with the inlet port and the explosion chamber, a piston, means carried by the piston and engaging the cam groove to reciprocate the piston through rotation of the rotor, a sleeve surrounding the rotor and extending through the explosion chamber, said sleeve provided with a slot with which the rear end of the spiral groove is adapted to periodically register and means for igniting a charge in the explosion chamber.

2. A gas turbine including a casing provided with a compression chamber, with an inlet therefor, with an explosion chamber, and with an exhaust from said explosion chamber; a rotor within the casing, said rotor being provided with a single port adapted first to establish communication between the inlet and the compression chamber and then between the compression and explosion chambers, said rotor cutting off communication between the two chambers after admission of a charge to said explosion chamber, a piston in said compression chamber, a connection between the piston and rotor to reciprocate the former through rotation of the latter to first draw a charge through the inlet and said single rotor port into the compression chamber and to then force the charge through said rotor port into the explosion chamber, means for igniting the charge in the explosion chamber while the latter is cut off from the compression chamber by the rotor, and rotor-controlled means for closing said exhaust until the charge is fired in said explosion chamber and for then opening said exhaust to permit escape of the fired charge under pressure to perform work.

3. A gas turbine including a casing provided with an intake and exhaust port, a rotor within the casing, means actuated by rotation of the rotor for drawing in and compressing a charge of fuel, means including the rotor for cutting off the compressed charge from the compressing means, rotor-

controlled means for closing said exhaust until the charge is fired and for then opening said exhaust to permit escape of the fired charge under pressure to perform work, and means for firing the charge while cut off from said compressing means.

4. A gas turbine including a casing provided with an intake and an exhaust port, a rotor within the casing, means actuated by rotation of the rotor for drawing in and compressing a charge of fuel, an explosion chamber, means carried by the rotor for admitting the compressed charge to the explosion chamber and cutting off the charge therein from the compressing means, rotor-controlled means for closing the exhaust port until the charge is fired and for then opening said port to permit escape of the fired charge under pressure to perform work, and means for firing the charge while cut off from said compressing means.

5. A gas turbine including a casing provided with an inlet and an exhaust port, and with an explosion chamber, a rotor within the casing, said rotor being provided with a spiral groove and a cam groove, and with a port adapted to alternately register with the inlet port and the explosion chamber, a piston, means carried by the piston and engaging the cam groove to reciprocate the piston through the rotation of the rotor, means for closing the rear end of said spiral groove until the charge is fired in the explosion chamber and for then opening said groove to permit outrush of the fired charge therethrough, and means for igniting the charge in the explosion chamber.

6. A gas turbine including a casing provided with an inlet and an exhaust port, and with an explosion chamber, a rotor within the casing, said rotor being provided with a spiral groove and a cam groove, and with a port adapted to alternately register with the inlet port and the explosion chamber, a piston, means carried by the piston and engaging the cam groove to reciprocate the piston through the rotation of the rotor, stationary means rotatably engaged by the rotor for closing the rear end of said spiral groove until the charge is fired in the explosion chamber and for then opening said groove to permit outrush of the fired charge therethrough, and means for igniting the charge in the explosion chamber.

7. A gas turbine comprising a cylindrical casing provided near one end with a transverse partition dividing it into a relatively large compression chamber and a comparatively small explosion chamber, said partition being formed with a central opening and with an off-center port, a tubular extension projecting from said one end of the casing in line with said central opening, a fuel inlet through the wall of said compression chamber near said partition, a rotor

having an enlarged intermediate portion within the casing in contact with the side of the partition toward said compression chamber and of a width to close said fuel inlet, said enlarged rotor portion having a peripheral port adapted first to establish communication between said inlet and said compression chamber and to later register with the aforesaid off-center port to place the compression chamber in communication with the explosion chamber; one end portion of the aforesaid rotor extending through said compression chamber while the other

end portion thereof passes through said central opening and is received in said tubular casing extension, a piston in said compression chamber surrounding said one end portion of the rotor and connected therewith to be reciprocated thereby; said other end portion of the rotor having a spiral gas-escape groove, means controlled by rotation of said rotor for closing the inner end of said groove until the charge is fired in the explosion chamber, and means for firing the charge.

BRYAN P. JOYCE.
